INVENTOR

EDGAR B. BICKER

By *Reuben S. Orwig*
ATTORNEY

UNITED STATES PATENT OFFICE.

EDGAR B. BICKER, OF ST. LOUIS, MISSOURI, ASSIGNOR TO MODERN PACKAGE CO., OF ST. LOUIS, MISSOURI, A CORPORATION OF MISSOURI.

PAPER CAN.

1,368,102.

Specification of Letters Patent.

Patented Feb. 8, 1921.

Application filed April 19, 1918. Serial No. 229,502.

To all whom it may concern:

Be it known that I, EDGAR B. BICKER, a citizen of the United States, and resident of St. Louis, Missouri, have invented certain new and useful Improvements in Paper Cans, of which the following is a specification containing a full, clear, and exact description, reference being had to the accompanying drawing, forming a part hereof.

10 My invention relates to improvements in paper cans, and my object is to construct a square can wholly of paper, including its seams, and in such a manner as to be least subject to distortion after forming.

15 My improvements consist in the novel construction, arrangement and combination of parts as will be fully, clearly and concisely set forth, definitely pointed out in my claim and illustrated by the accompanying drawings, in which—

Figure 1 is a plan view, on a reduced scale, of the blank, for the walls of the can.

Fig. 2 is a fragmental plan view of the blank for the can bottom,

25 Fig. 3 is an enlarged fragmental, sectional elevation, taken on the line 3—3 of Fig. 1 showing a crimp to form one of the can corners.

Fig. 4 is an enlarged fragmental sectional elevation, taken on the line 4—4 of Fig. 1, showing a stop bead for the lid.

Fig. 5 is an enlarged fragmental sectional elevation, taken on the line 5—5 of Fig. 1 showing a channel which facilitates the securing of the bottom.

Fig. 6 is a fragmental inverted plan view showing the bottom as secured to the walls.

Fig. 7 is a sectional plan taken on the line 7—7 of Fig. 8, showing the lap seam 40 of the side walls.

Fig. 8 is an elevation, partly in section, of the complete can.

Fig. 9 is a plan of a blank for the innermost ply of the lid.

45 Fig. 10 is a plan of a blank for the outermost ply of the lid.

Fig. 11 is a fragmental, inverted plan showing the folded arrangement of the corner elements of the innermost ply of the 50 lid.

Fig. 12 is a view similar to Fig. 11 showing the folded arrangement of the corner elements of the outermost ply.

Fig. 13 is an inverted plan of the complete lid.

55

Fig. 14 is an edge view of the lid.

Fig. 15 is an enlarged fragmental sectional elevation, taken on the line 15—15 of Fig. 13.

Fig. 16 is an enlarged fragmental sectional elevation, taken on the line 16—16 of Fig. 13, 60 and

Fig. 17 is an enlarged fragmental sectional elevation taken on the line 17—17 of Fig. 13.

Referring to the drawings by numerals, 18 designates the full wall sections of the 65 wall blank and 19 and 20 the end wall sections thereof, the section 20 having greater width than the section 19.

Extending the height of the blank between the wall sections are the sectionally 70 curved creases 21, which as shown extend to the top margin, but terminate short of the bottom blank margin, but whose lengths or heights are co-extensive with the heights of the walls proper.

At the bottom end of each crease 21 there is a cutout or notch, 22, forming the crimping flanges 23 which serve to secure the bottom of the can to the walls, and in each flange 23, next the lower margin of the 80 walls proper and for their lengths is a pressed channel 24.

Near the upper margin of each wall section there is a stop bead 25, paralleling the said margin.

Fig. 1 shows an inside face view of the wall blank, and in this illustration the creases 21 are pressed outwardly.

The stop beads 25 are pressed outwardly and the pressed channels are in the inside 90 faces only of the material, as shown in Figs. 3, 4 and 5, respectively.

The bottom proper 26 is substantially rectangular, with dimensions between its margins 27 equivalent to the widths of the wall 95 sections, recited, and its corners 28 are rounded and with radii corresponding to the curvatures of the creases 21 of the wall blank.

Along each margin of the bottom and approximating their lengths, save for the 100 rounded corners, is a flange 29, and preferably to facilitate their bending to a right angle relative to the bottom proper, a weakened line 30 is provided between each flange and the bottom proper.

105 The bottom with its flanges bent as recited

is held and the wall blank is positioned therearound with its pressed channels disposed to receive the flanges of the bottom, and its curved creases 21 registering with the 5 round corners of the bottom.

Then with glue or other adhesive, which is applied prior to the assembling, the wall blank is wrapped about the bottom, commencing with the section 19, which is approximately a half wall, then the full wall sections 18 and finally the section 20, which has been "gummed" along its free edge for securing or seaming to the half wall section 19, as shown in Fig. 7.

15 The flanges 23, are then turned as shown in Figs. 6 and 8 to embrace the flanges of the bottom, with the understanding that their surfaces, preferably both the flanges of the wall blank and the flanges of the bottom have been copiously coated with adhesive.

By reason of the sectionally curved crease 21, between the wall sections there is no tendency toward "springing" at the wall corners and thus the can is subject to a minimum of distortion and with wall sections most likely to hold smooth and unwarped.

As has been recited, the can is "all paper" including its cover or lid, hence it is essential that the upper margins of the walls be held in "true square" in order to permit ready placement and removal of the cover, and this is accomplished, between corners by the beads 25.

35 The cover is made up of two blanks whose bodies 31 and 32 are shaped to conform with the cross section of the can, that is, each substantially rectangular and with rounded corners 33 and 34 of radii substantially 40 that of the radii of the can corners.

The body or blank 31, which is the inside 45 ply of the cover is preferably made from relatively heavy or thick stock and along each margin provided with a flange 35 which extends or laps beyond the "cut" of the round corner 33 and each lapping is such as to bring the terminals of the flanges to abut each other at the "center" of the round corner when the flanges are turned 50 to a right angle relative to the body.

The body or blank 32 which is the outside 55 ply of the cover, is relatively thin whereby

it may serve as a "finish" and its body dimensions are substantially the same as the body or blank 31, and like the blank 31 55 its corners are rounded, and it is further provided with flanges 36, similar to the flanges 35, of the "inside" blank, except that the extended ends thereof project beyond the cuts for the round corners, so that they 60 may be relatively overlapped, and to completely overlie the extended ends of the flanges 35.

By preference the whole inside face of the blank or body 32 is supplied with adhesive 65 or gummed and thus formed over the heavier inside blank or body 31.

By reference to Figs. 13, 16 and 17 it will be noted that the relatively thin outer flanges 36 are adhesively secured over the 70 margins of the round corners of the heavier body 31, and thus I am enabled to make a neat and firm flanged cover corner on a round-cornered square can.

The heights of the flanges of the cover 75 are approximately equal to the distance between the bead 25 and the top edge of the can so the cover will be supported by the flanges and hence not be subjected to tearing at their corners by "jamming" the cover 80 over the can to the extent of the can-top edge breaking through the cover.

By reason of the "copious" application of adhesive to the relatively secured flanges of the bottom and walls I obtain more than a 85 mere securing of the flanges, for when dried the adhesive serves to strengthen and stiffen the whole bottom end of the can.

I claim—

As a new article of manufacture, a can, 90 constructed of a single blank of paper, of substantially square section and provided with round corners, said round corners being creased in the blank prior to the squaring of the can, and an end closure for the 95 can constructed of two blanks each having round corners and marginal flanges the flanges of the one blank of the closure at each corner having combined lengths equal to the linear dimension of the corner and 100 the flanges of the other blank having combined lengths in excess of the linear dimension of the corner.

EDGAR B. BICKER.
